UNITED STATES PATENT OFFICE

EGIDIO GARUFFA, OF MILAN, ITALY

INTERNAL-COMBUSTION ENGINE

Application filed January 22, 1926, Serial No. 82,952, and in Italy January 23, 1925.

The present invention relates to internal combustion engines and more particularly to a two-cycle engine.

While the present invention may be used

for other purposes, it is particularly adapted for air-craft engines, where the weight of an engine is of particular importance. In such uses, a two-cycle engine is preferred on account of its low weight per horse power.

10 Heretofore, four-cycle engines have been employed in spite of the extra weight due to the fact that previous two-cycle engines have not been sufficiently dependable to warrant their adoption. Further, in two-cycle engines, the scavenging is not thorough and there is considerable waste of gas in the operation. These and other obstacles render the usual type of such engine much less desirable than the four-cycle engines.

20 The present invention overcomes these difficulties by providing a source of compressed air for thoroughly scavenging the cylinder and an independent source of compressed air adapted to be saturated with gasoline which is forced into the cylinder subsequent to the scavenging operation and slightly prior to the closing of the exhaust port. In this way there is no waste of fuel; at the same time the scavenging may be as thorough as desired.

30 A suitable blower or fan having a plurality of stages may be utilized so that the number of stages may be changed as the altitude increases whereby a substantially constant pressure may be maintained in the air and fuel mixture supplied to the cylinders. In this manner the power of the engine remains constant and its operation is not affected by the varying changes in height and the corresponding changes in the density of the atmosphere.

40 An object of the present invention is to provide a compact motor particularly suited for air-craft uses which has a high volumetric thermal efficiency and capable of maintaining a constant output at high altitudes.

45 Another object of the invention is to provide a thorough scavenging of two-cycle engines without waste of fuel and to supply to the engine substantially constant quantities of fuel irrespective of the density of the atmosphere.

Another object of the invention is to provide an inexpensive aircraft motor which is simple in construction and effective in operation and not subject to breakdowns.

50 Other and further objects of the invention will be obvious upon an understanding of the illustrated embodiment about to be described; and various advantages not referred to herein will occur to one skilled in the art upon employment of the invention in practice.

55 Fig. 1 is a sectional view through one cylinder of the motor showing the arrangement of the scavenging and exhaust ports;

Fig. 2 is a work diagram illustrating the 60 opening and closing of the various ports;

Fig. 3 is a diagrammatic illustration of the 65 compressed air and fuel mixture supply systems;

Fig. 4 is a side elevational view partly 70 diagrammatic of a motor embodying the present invention; and

Fig. 5 is a diagrammatic illustration of a 75 gas turbine for operating the blower or fan.

Referring to the drawings and more particularly to Fig. 1, there is shown a cylinder C having an exhaust port s and scavenging ports a and b. The ports a and b are positioned so that the port b is slightly higher than the exhaust port s. That is, the piston uncovers the port b prior to the exhaust port 80 on its downward stroke and closes the exhaust port prior to the closing of the port b on its compression stroke. The lower port a of each cylinder is fed with compressed air supplied by a suitable fan or blower at a predetermined pressure. The pressure tube Ta connected to the fan or blower Q may be used for this purpose. The upper port b is fed with a rich fuel mixture which may be air and gasoline under the control of a distributor 85 which is preferably a rotary one as shown at V. The distributor opens and closes the tube Tb leading to the port b in timed relation with the movement of the piston.

90 The two tubes Ta and Tb may be fed by a single fan or blower q, it being understood that a suitable fuel mixture is injected into the tube Tb. During the downward stroke of the piston the tube Tb is closed by the distributor V. As the exhaust port s is uncov- 95 100

- ered air is admitted under pressure through the tube T_a and exhaust port a which scavenges the cylinder thoroughly due to the shape of the piston head. The irregular shape of the piston deflects the air toward the head of the cylinder and forces out the burnt gases. Since there is no fuel being delivered to the cylinder at this time, an escape of the compressed air through the exhaust port is unimportant, therefore all of the exhaust gases may be removed without waste of fuel. As the piston reaches the end of its stroke and begins its compression stroke, the distributor V admits a rich fuel mixture into the cylinder just prior to the closing of the exhaust port and continues for a short time after the exhaust port s and port a are closed. In this way any desired fuel charge may be supplied without waste.
- 20 The work diagram of this operation is shown in Fig. 2. The circle having its center at O , represents the path of the crank and its vertical diameter M represents the stroke of the piston. During the stroke portion 25 $A-B$, the port b is closed by the distributor which feeds the cylinder with fuel. During the portion $B-C$ compressed air is supplied through port a and during portion $C-D$ the exhaust portion s is open. By drawing a horizontal line through the points A, B, C, D and E , the total height h of the supply and scavenging ports and the total height h^1 of the exhaust ports are obtained. The point A is considerably above the point D , representing the closing of the fuel port b and exhaust port s , respectively. During the down stroke of the piston, the port b is closed and no fuel enters the cylinder. When the piston reaches the line $D-D^1$ the exhaust port is open and the exhaust continues through the angle DOD^1 , while air is supplied during the period represented by the angle BOB^1 . By means of the distributor V controlling the fuel port b the admission of air and gasoline begins at the point F and continues through the stroke represented by the angle FOA . In this manner the initial scavenging is effected with air only and leakage is of little importance. The mixture is introduced shortly before the exhaust port closes and continues for a short period after the closing. The fuel supply and the scavenging being effected by two independent gaseous currents of different qualities produces the best conditions for obtaining complete scavenging and prevents loss of fuel through the exhaust port. It permits complete elimination of smoke and the complete filling of the combustion chamber with the fuel mixture.
- 50 While any type of fan or blower may be used the preferred embodiment contemplates a turbo-compressor operated by a suitable motor or by an exhaust gas turbine as shown in Fig. 3. The blower may be connected through the engine crank shaft $O-O$

through the pinion R on the shaft $X-X$ of the blower in any suitable manner.

Preferably the turbo blower has four stages (I-IV) and can deliver the quantity of air necessary for scavenging the cylinder at a predetermined pressure. The rotation of the blower may be effected by the turbine T operated by the exhaust gases. In order to prevent too great an angular velocity the turbine is of a two-stage construction. It receives the exhaust gases from the engine through the exhaust pipe s and discharges the gas at S^1 .

Since the blower is also connected to the engine through crank shaft $O-O$, two separate drives are provided and a suitable clutch I permits the blower to be driven directly by the engine through the pinion R when desired. Accordingly if the turbine T fails to function the blower may be driven by the engine or if greater power is desired than afforded by the turbine T , both the turbine and the engine may be used or the engine alone.

In order to obtain constant power at different heights, it is desirable that the engine should be fed with a constant weight of air and also with a constant weight of gasoline. The present blower accomplishes this by having the valves Z^{III} and Z^{IV} . While flying at considerable altitudes the air may be taken from the fourth stage through valve Z^{IV} which increases the pressure. The volume may be increased simultaneously through the speed change gear on shaft $X-X$, which preferably permits the blower to operate at three different angular speeds, n^1, n^2, n^3 .

As volumes and pressures are nearly related to square of annular speeds both will increase, passing from n^1 to n^2 according to the relation

$$\frac{n-2^2}{n-1^2}$$

and passing from n^1 to n^3 according to relation

$$\frac{n-3^2}{n-1^2}$$

Increasing the volume and pressure also increases the power required to operate the blower; but the discharging exhaust gases possess the necessary energy and in any event direct coupling with the engine can be used if desired.

Atomization of the gasoline is effected in the tube T_b by an atomizer V which is adjustable to vary the amount of fuel fed as desired. Gasoline is supplied from a receptacle H through tube 2. Pressure in this receptacle is preferably greater than the scavenging pressure so as to obtain very fine atomization which is facilitated by the heat of the compressed air.

Fuel is supplied to the receptacle H by any suitable means here shown as a pump W .

This pump may be driven either by the engine or by a small air propeller if used in aircraft. The tube 2 connects the atomizer V with the lower portion of the receptacle and a tube 3 is connected to a suitable compressor which delivers air through the automatic valve γ from one of the engine cylinders. The automatic valve 4 is adapted to discharge any excessive pressure in the receptacle. The tank H is also provided with a pet cock 6 for discharging gasoline and a monometer 5.

One form of engine is shown in Fig. 4 having a motor casing A with a base portion B. Six cylinders are shown, C_1 , C_2 , C_3 , C_4 , C_5 , and C_6 . The gas turbine T is shown at the front end thereof for driving the fan or blower S. A mechanical drive direct from the engine is shown through pinion R. The speed control gear C_v and the tubes T_a , T_b are shown connected to the respective cylinders by T branches. The fuel supply tank H and atomizer V are properly connected as described hereinbefore.

In Fig. 5, the gas turbine T is shown arranged adjacent the turbo-blower S on shaft O—O. The speed control gear C_v is mounted on the front end of the shaft O—O and drives the hollow shaft O_1 — O_1 telescoped about the shaft O—O.

As various changes may be made in the above embodiment without departing from the spirit of the invention, it is to be understood that all matter herein set forth is to be interpreted as illustrative and not in a limiting sense.

Having thus described my invention, I claim:

1. A two-cycle internal combustion engine comprising a plurality of cylinders, a turbo-blower having a plurality of stages therein, means for supplying air from said blower to said cylinders from different stages of said blower, and means for driving said blower at variable speeds to increase the volume of air delivered to the cylinders independently of the speed of the engine.

2. A two-cycle internal combustion engine comprising a plurality of cylinders, a turbo-blower having a plurality of stages therein, means for conducting air from different stages of said blower to said cylinders for scavenging same, and means for conducting air from said blower to an atomizer for supplying fuel to said engine.

3. A two-cycle combustion engine comprising a cylinder, a turbo-blower having a plurality of stages therein and means for supplying air from said blower to said cylinder from different stages of said blower for scavenging same, means for driving said blower at variable speeds to increase the volume of air delivered to the cylinder, and devices for connecting different stages of said

blower with an atomizer for supplying fuel to the cylinders.

4. A multi-cylinder engine the combination of air compressing means for supplying air under pressure to said cylinder, a turbine operated by the exhaust gases for driving said compressing means, and devices for connecting said compressing means directly to the engine to be driven thereby.

5. A multi-cylinder engine the combination of a multistage air compressing means for supplying air under pressure to said cylinders from different stages thereof, means operated by the exhaust gases for driving said compressing means, and a clutch for connecting said compressing means directly to the engine to afford greater power for the operation thereof.

6. A multi-cylinder engine for aeroplanes and the like, the combination of compressing means for delivering compressed air to said cylinders, devices adapted to be operated by the exhaust gases for driving said compressing means, said compressing means being adapted to be driven also by the engine, and a mechanism for connecting said means either to said engine or to said devices.

7. In a two-cycle engine of the class described, the combination of a distributor for supplying a mixture to said cylinder, a reservoir for liquid fuel and means for maintaining the pressure in said reservoir greater than the scavenging pressure, said means comprising a connection with one of said cylinders to render the explosive pressure effective thereon.

8. In a two-cycle internal combustion engine, the combination of a multistage compressor for supplying scavenging air to said engine, a distributor for supplying a fuel mixture to said cylinder, a reservoir having a supply of liquid fuel, and means for maintaining a pressure in said reservoir greater than the scavenging pressure in said engine to assure proper operation of said distributor at all times.

9. In a two-cycle internal combustion engine, the combination of a multistage compressor for supplying scavenging air to said engine, and for supplying air to said distributor, a distributor for supplying a fuel mixture to said engine, a reservoir for fuel and means connected with a cylinder head for maintaining a pressure in said reservoir adequate to supply fuel to said distributor at all pressures to which the distributor is subjected.

Signed at Milan, Italy, this 4th day of January, 1926.
